UNITED STATES PATENT OFFICE

159,177

BAG OR THE LIKE

Oscar L. Vines, New York, N. Y.

Application April 14, 1948, Serial No. 145,720

Term of patent 14 years

(Cl. D58—2)

To all whom it may concern:

Be it known that I, Oscar L. Vines, a citizen of the United States, residing in New York city, county of New York, and State of New York, have invented a new, original, and ornamental Design for a Bag or the like, of which the following is a specification, reference being had to the accompanying drawing forming part thereof.

In the drawing:

The back of the bag is the same as the front thereof, except that it does not have a longitudinal slot, as is indicated in Figure 1.

I claim:

The ornamental design for a bag or the like, as shown and described.

OSCAR L. VINES.
